UNITED STATES PATENT OFFICE.

CHARLES LOWTHER, OF NEW YORK, N. Y.

DRIVING APPARATUS.

SPECIFICATION forming part of Letters Patent No. 340,513, dated April 20, 1886.

Application filed December 22, 1885. Serial No. 186,493. (No model.)

To all whom it may concern:

Be it known that I, CHARLES LOWTHER, of the city, county, and State of New York, have invented a certain new and useful Improvement in Driving Apparatus; and I do hereby declare that the following is a full, clear, and exact description of the same, reference being had to the accompanying drawings, forming part of this specification.

10 Similar letters refer to similar parts in the drawings.

My invention relates to a muff or hand-protector, combined with reins or holders for driving, which will completely protect the hands 15 of the driver from cold, while it enables him to hold the reins securely, and, if required, to adjust them to various lengths, and in proper cases to otherwise conveniently handle them.

Figure 1 is a cross-sectional view through 20 the center of one of my hand-protectors, showing an arrangement of the same with reference to the reins to be held while the hand is thus protected. Fig. 2 is a cross-sectional view of 25 the same apparatus, taken at right angles to the view shown in Fig. 1. Fig. 3 is a view of the outside of one of my hand-protectors, showing a form of catch or attaching-plate, by 30 which the two hand-protectors can be securely connected together, thus enabling the driver, if need be, to withdraw either hand at will 35 from the protector, while he securely holds both reins with the remaining hand in the other protector. Fig. 4 is a view of a form of plate to be attached to the other hand-protector, and which is intended to engage with the plate shown in Fig. 3.

In the drawings, A represents a hand-protector. It is of suitable size to allow the insertion of the hand of the driver, and roomy 40 enough to allow the handle of the holder of the rein, which is arranged within it, to be grasped by the hand.

The muff is preferably made at the open 45 end of gauntlet-shape, so as to cover the sleeve of the wearer and protect the wrist from cold. In material it should be made thick and warm, of any material; but I recommend the use of fur on the outside, with a suitable lining on the inside. The front or forward end of the 50 hand-protectors are closed or substantially closed to prevent admission of cold.

B is the rein. It is made to extend from the

front end of the protector, and is arranged either to pass directly through the front end into the interior of the protector, where it can be 55 grasped or held, or to be attached to the front end of the protector to a holder, loop, or other suitable and convenient contrivance extending within the protector, for holding or grasping the rein. I have shown a stirrup form of 60 holder or loop attached to the rein, and arranged within the protector at C. This holder is, in the form shown in the drawings, grasped by the hand. For this form of holder a suitable loop or other convenient arrangement of 65 the part of the rein to be attached may be substituted; but the stirrup form is especially advisable, on account of the facility with which it may be grasped and held by the hand, particularly in cold weather. If the rein itself 70 does not pass directly within the protector at its front end, it should be attached by a strong holding device to the front end of the protector. The form of device that I have selected and illustrated in the drawings is that of the 75 ordinary tongueless buckle, which is usually attached to the above-mentioned holders or loops, through which the rein may pass and be extended through the inside or down the outside of the muff or protector until it comes 80 to the open end of the hand-protector, where it may pass through a loop connected with the holder on the inside of the protector, thus securing them both together at the open end of the protector. This arrangement will allow 85 the reins to be adjusted to any length at will, and the ends will be held in convenient position by the loop at e, where they may be grasped by the hand in an emergency, if desired.

90 Other forms of attaching-connections between the rein and the hand-protector may be substituted for the buckle. (Shown at f.)

On the outside of my hand-protectors I apply devices which permit the engagement of 95 the two protectors together.

Fig. 3 shows a form of plate or catch, g, which is securely attached to the body of the hand-protector or to the rein or holder on the inside, by riveting, sewing, or otherwise. This 100 plate has an aperture in it, into which the stud h, (shown in Fig. 4,) engages. This stud should be securely attached by a plate or otherwise, and be riveted or attached in the same

manner as plate *g* to the opposite muff or hand-protector. By the use of these devices it will be apparent that if the driver using the protectors desires to withdraw one of his hands 5 from one of the protectors for the purpose of using the whip, or otherwise, he may, by engaging the stud *h* with the corresponding aperture in the plate *g*, fasten both protectors together, and by that means hold and control both 10 reins (one of which is attached to each of the protectors) by the hand inserted in one of them, and upon inserting the hand again disengage them at will.

Other devices for securing the engagement 15 between the two protectors may of course be substituted for the plate *g* and stud *h*, as I do not claim anything novel in that particular form of engagement, except as applied to my new structure.

What I claim, and desire to secure by Letters Patent, is—

1. The combination, with a rein, of a hand-protector open at the rear and closed at the forward end, and provided with a stirrup-formed holding device arranged in the interior 25 of the same for holding the reins, substantially as shown and described.

2. The combination of reins with two hand-protectors, substantially such as described, provided with a plate, *g*, and stud *h*, or equivalent devices, for engaging the hand-protectors together and disengaging them at will, substantially as and for the purpose set forth.

CHARLES LOWTHER.
